UNITED STATES PATENT OFFICE

JESSE FULENWIDER AND HARRY FULENWIDER, OF SAVANNAH, GEORGIA

METAL ROOFING-SHINGLE CONSTRUCTION

Application filed May 18, 1928. Serial No. 278,733.

This invention relates to improvements in metal roofing shingles, and more particularly to a novel construction of lock fastener which will be positioned at the top of each shingle 5 to assist in holding the shingle in place on the roof, and to positively prevent water from blowing underneath the edges of the shingle.

An object of the invention is to provide an improved lock fastener for metal roofing shingles, which will be formed separately from the shingles, and will be attached to the upper edges of the same, in any desired manner, whereby water will be prevented from being blown beneath the edges of said shingles.

15 A further object of the invention is to provide an improved form of metal roofing shingle with tongue and groove side edges and a separate lock fastener at the top of the shingle which will be positively engaged by the lower 20 edge of an upper row of shingles to produce a waterproof joint that will preclude any chance of water from blowing underneath the same.

25 A still further object of the invention is to provide an improved lock fastener for metal roofing shingles, which will be formed separately from the shingle, and will be attached to the shingle in any desired manner, and will be adjustable with respect thereto.

30 Other objects will appear as the description proceeds.

In the accompanying drawings which form a part of my application,

Figure 1 is a plan view of several metal roofing shingles as they will appear on a roof;

Figure 2 is a separated perspective view of the shingles, showing the manner in which the same are interlocked together;

40 Figure 3 is an enlarged vertical sectional view taken through several courses of shingles;

Figure 4 is a sectional view taken on the line 4-4 of Figure 1;

45 Figure 5 is an enlarged sectional view taken on the line 5-5 of Figure 1, and

Figure 6 is a perspective view of my improved lock fastener positioned at the top edge of each metal shingle.

50 Like characters of reference are used

throughout the following specification and the accompanying drawings to designate corresponding parts.

Our improved metal shingle 1 is preferably formed rectangular in shape, and is provided 55 with a longitudinally extending tongue 2, and a spaced longitudinally extending rib 3 at one side edge thereof, and a longitudinally extending rib 4, and a groove 5 spaced from said rib 4 and extending parallel therewith. 60

The upper or top edges of the shingles 1 are bent upwardly at right angles to form a lip 6 which engages and interlocks with a separately formed lock fastener 7, in such a manner that a portion of the fastener underlies the body of the shingle and extends upwardly in contact with the portion 6 of the shingle, and is bent thereover, and downwardly, and along the upper surface of the shingle, terminating in a slightly upturned lip 8. 70 These lock fasteners are formed separately from the shingles, and are attached thereto at their top edges in any desired manner by special machinery (not shown).

The lower edges of the shingles are bent 75 downwardly at a slight angle, and then inwardly to form the locking lips 9, which cooperates with the lips 8 of the lock fasteners 7. The under side of the shingles will rest on the upturned portion of the lock fastener, 80 and thereby be automatically and properly spaced.

The shingles may be attached to the roof in any desired manner.

It will be apparent that the shingles will be 85 self-spacing, and will readily interlock with each other to produce a metal roof which will positively prevent the wind or water from blowing underneath the shingles, thereby assuring a waterproof roof which will stand a 90 maximum service of wear.

The shingles will be laid in courses, from the bottom of the roof to the top.

As before mentioned, the lock fasteners may be attached to the shingles by special machinery, but it will be understood that the same may be secured thereto by soldering, cementing, welding, or in any desired manner. If desired, the lock fasteners may be merely clamped to the shingles, thereby permitting 100

of adjustment between the fasteners and shingles if necessary.

Many minor changes in detail of construction may be resorted to without departure from the spirit of the invention.

Having thus described our invention what we claim as new and desire to secure by Letters Patent of the United States is:

1. In a metallic roof construction, the combination of a plurality of metal shingles, having upturned lips at their upper ends and downwardly turned locking lips at their lower ends, separately formed lock fasteners secured at the top edges of said shingles, said fasteners comprising a lower flange underlying the body of the shingle and a loop portion extending upwardly and then downwardly to embrace the upturned lip at the upper end of the shingle, and an upper flange 20 contacting with the upper surface of the shingle and provided at its free end with an upturned lip to receive the lower locking lip of a shingle in a superjacent course.

2. In a metallic roof construction, the combination of a plurality of metal shingles having upturned lips at their upper ends and downwardly turned locking lips at their lower ends, separately formed lock fasteners secured at the top edges of said shingles, said fasteners comprising a lower flange underlying and contacting the body of the shingle and a loop portion extending upwardly and then downwardly to embrace the upper end of the shingle, and an upper flange 35 contacting with the upper surface of the shingle and provided at its free end with an upturned lip to receive the lower locking lip of a shingle in a superjacent course.

In testimony whereof we affix our signatures.

JESSE FULENWIDER.
HARRY FULENWIDER.
